HEATING SYSTEM

Harold R. Goodale, Bristol, Conn.

Application December 30, 1939, Serial No. 311,713

29 Claims.

(Cl. 237—9)

This invention relates to heating systems, especially one-pipe steam systems using vacuum valves, and comprises all of the features and aspects of novelty herein disclosed. According to the Ferguson Patent 2,062,565, it is desirable to bring the pressure in a steam heating system back to atmospheric at the beginning of each heating cycle because, with air in the system, the venting of this air and consequent distribution of steam to the radiators can be better controlled. In the patent, an electrically operated valve is used to break the vacuum and this is complicated and expensive.

An object of the invention, accordingly, is to provide an improved and an inexpensive valve for breaking vacuum, and more especially a valve and an improved method of operating a heating system whereby electric operating means for the valve is eliminated and wherein the opening of the valve to break vacuum will be controlled by changing conditions within the system itself. In the present embodiments, the vacuum is broken under control of a change in pressure in the system, this change in pressure preferably being the increase in vapor pressure due to renewed heat after a partial vacuum has been built up by the cooling of the system. This method of operation is conducive to simplicity and low cost.

To these ends and also to improve generally upon devices and methods of this character, the invention consists in the various matters herein-after described and claimed. In its broader aspects, the invention is not necessarily limited to the specific constructions and steps selected for illustrative purposes in the accompanying drawings in which

Fig. 1 is a diagram of a portion of a heating system.

Fig. 2 is a sectional view of a valve.

Fig. 3 is a sectional view of the valve of Fig. 2 partly broken away and with parts in another position.

Fig. 4 is a sectional view, partly broken away, of a modified valve.

Fig. 5 is a sectional view taken on line 5—5 of Fig. 4.

Fig. 7 is a sectional view, with parts broken away, of a modified valve.

Figs. 8, 9 and 10 are sectional views similar to Fig. 7 showing successive positions taken by some of the parts of Fig. 7.

Fig. 11 is a sectional view of another modification.

Figs. 12, 13 and 14 are sectional views of other modifications.

Fig. 15 is a diagram.

The numeral 10 indicates a furnace fired by an

oil burner controlled by a motor M. A steam main 12 leads from the furnace to points below the various radiators 14 while risers 16 lead to the radiators. Each radiator has a vacuum valve 18 with an adjustable vent. One of my vacuum breaking valves V is shown attached to the furnace main 12 but can be placed on a radiator. The motor circuit is controlled by a thermostat 22 in another circuit which operates a relay switch 24. In a system lacking a vacuum-breaking valve, the pressure changes in the system that might occur during a heating cycle are indicated by the curve on the chart, Fig. 15. The heavy lines indicate periods when the burner is on and naturally the pressure then rises. In a system using the electrically operated vacuum breaking valve of the Ferguson patent, the thermostat starts the burner simultaneously with the breaking of vacuum in the system, and a solenoid, a switch and a connected bellows, among other things, are needed to operate the vacuum breaking valve. In this system, the pressure would go up to atmospheric on dotted line L. According to the present invention, my vacuum breaking valve is controlled by pressure in the system itself and the air is not let in to break the vacuum until the burner has reheated the water to a point at which some vapor pressure (diminished vacuum) is created. In such a system, the pressure, instead of going up gradually as in the full line curve of the chart, would go up suddenly to atmospheric at the point P as indicated by a broken line. The air in the system then gives definite control of venting through the vacuum valves on the radiators.

One form of my valve to go directly on the furnace is shown in Figs. 2 and 3. A base 30 is threaded to receive a flanged nut 32 which clamps a flange 34 on a casing 36. At the top of the casing is a threaded member 38 having a tapped opening to receive the adjustable threaded stem 40 of a valve 42 which is conical and adapted to engage a seat in a movable seat member 44. Attached to and movably supporting the seat member is a bellows 46 whose lower end is soldered to the casing. Atmospheric air has access to the space outside of the bellows through a screened opening 47. Resting on the seat member is a light check valve 48 in the form of an apertured disk adapted to slide down on the stem 40 as far as the shoulder of the valve 42 when the seat member moves down. The seat member has a central port 50 leading to a second seat with which a second conical valve 52 cooperates. The valve 52 has a stem 53 adapted to slide within a sleeve 54, such sliding being restricted by a friction brake in the form of a spring clip 56 having a shoe 58. A cap 60 loosely surrounds the stem 53 below the shoulder and is

threaded on the seat member. A port 55 provides communication between the interior of the bellows and the port 50.

The sleeve 54 is supported for self-aligning movement on a ball 56 which projects from a recess in an extended portion of a plug 60 threaded in the base. The sleeve is held down permanently by a tension spring 62 fixed to the sleeve and soldered to the base. The base has a threaded nipple 64 adapted for attachment to the furnace as indicated by 36 in Fig. 1. In this case, the valve V on the main 12 would be an ordinary vacuum valve to vent air and retain a partial vacuum.

Starting with a cold system, the upper valve 42 being closed and the lower valve 52 open, the heat comes on and steam pressure only tends to stretch the bellows and close the valve tighter. Air in the system is driven out of the usual vacuum valves 18 on the radiators. A period of heating occurs. When the heat is shut off, condensation builds up a partial vacuum. This causes the bellows to contract, thereby drawing the seat member 44 down away from the valve 42 as indicated in Fig. 3. Air does not enter the bellows to any extent because the check valve 48 remains on the seat until the seat member 44 goes down far enough to leave the check valve supported on the shoulder of the valve. As the seat member thus descends, it engages the lower valve 52 and closes the port 50 before the check valve is unseated. Thereafter the contraction of the bellows causes the seat member to push the stem 53 down in the sleeve 54 against the friction of the spring-pressed shoe to the position shown in Fig. 3. If there is no material leakage of air into the system, vacuum will be held until the heat comes on and creates a vapor pressure. This reduces the vacuum, partially expands the bellows, and opens the lower valve which breaks the vacuum completely. The entering air expands the bellows, lifting the seat member and the valve stem 53. The seat member also lifts the check valve 48 off the shoulder and, after this occurs, air can only continue to enter by leaking between the valve stem and the check valve. The valve 42 finally becomes closed and all the parts reach the original position.

It will be appreciated that, during the building up of vacuum, the greater the vacuum, the more the friction stem 53 will slide down in the sleeve 54 to limit the pressure which the vacuum acting on the bellows tends to exert between the valve seat and the valve 52. Hence, however high the vacuum builds, substantially the same diminution in vacuum will cause the valve seat and the valve to separate and this degree of diminution is predetermined by the resistance to sliding of the spring pressed stem 53 in the sleeve 54.

In Fig. 4, is shown a valve to be mounted at V in Fig. 1 and used with the radiator valves 18 (but without the valve 36). It comprises a base 10 which is threaded to receive a flanged nut 12 which clamps a flange 14 on a casing 16 against a gasket 18. A supporting ring 20 is clamped in a recess of the base and is soldered to a bellows 22 to which a valve seat member 24 is attached. The seat member has a conical seat 26 for a valve stem 28 which is formed as a part of a disc 30. The disc has vertical grooves at opposite sides in which stiff wires or rods 32 are soldered, the upper ends of the rods being bent over at 34 onto opposite ledges 36 on the seat member. The rods have enlargements 38 such as flattened areas which are arranged to slide vertically in vertical

grooves 100 in the threaded nipple 102 of the base. The enlargements are pressed against the bottoms of the grooves by a U-shaped spring 104 having openings smaller than the enlargements. The two rods and the attached disc 30 and valve stem 28 are thus frictionally supported but can be forced down whenever the bellows collapses enough for the seat 26 to press against the valve stem 28.

There is an annular space between the valve stem 28 and the surrounding seat member and this space communicates by a vertical port 106 and transverse grooves 108 with the space outside of the bellows. A partition 110 extends across the casing and has a central hump 112 and a plurality of struck-up lugs 114 which leave perforations 116 which provide communication between the compartments. Resting on the hump 112 and centered by the lugs 114 is a snap disc 118 forming the bottom of a thermostatic member in the form of an alcohol float 120 having an attached valve stem 122 arranged to engage a seat in an adjustable seat member 124. There is an annular space between the valve stem and the seat member and this space communicates with the atmosphere through a port 126 which should be of larger cross section than the port 106. The valve stem 28 can be removed endwise by first removing the spring 104 and turning the rods 90° until the lugs 36 pass beyond the ends of the ledges 36. The removal of the nut 12 provides for access to the bellows.

Assuming both valves are open and the system is cold, when the heat comes on, vapor pressure drives air out of the casing, such air passing through the lower seat member 24, the perforations 116 and the upper port 126. When steam arrives at the alcohol float, the upper valve 122 closes. A period of heating ensues. When the fire dies down, condensation builds up a partial vacuum and, upon sufficient cooling, the upper valve opens. Air freely enters the casing above the bellows, collapsing it partially, and depresses the lower seat member 24 to close the lower valve. Since the upper port 126 is larger than the lower port 106, the air does not enter the bellows sufficiently to destroy the partial vacuum. As condensation continues and more of a vacuum forms inside of the bellows, the latter collapses more and more and the seat member 24 pushes down on the valve stem 28. The stem in turn pushes down on the two rods overcoming the friction provided by the spring-pressed enlargements 38 which slide downwardly in their grooves. When, later, the heat comes on again, vapor pressure (diminished vacuum) will easily expand the bellows and raise the valve seat 26 from the valve 28. Then both valves are open to admit air to the system. As the valve seat rises to thus open the lower valve, the ledges 36 engage the lugs 36 on the rods, and an increase in vapor pressure lifts the rods and the valve stem 28, the latter staying open and in spaced relation to its seat. The parts thus return to the original position ready for another cycle.

In Fig. 7, another valve for use at V comprises a base 130 threaded to receive a flanged nut 132 which clamps a flange 134 on a casing 136 against a gasket 138. At the top of the casing is a seat member 140 enclosed by a cap 142 having a port 144. A set screw 146 in the cap clamps a supporting wire or rod 148 in adjusted position vertically. Slidable on the rod and having clearance therewith is a hollow valve 150 adapted to seat against the member 140 and having a projecting

tube 152 which always projects through the member 140 to let atmospheric air enter into a float or container 154 on which the valve 150 is secured. The container 154 is guided in the casing by struck out projections 156. A collar 158 on the rod supports the center of a bimetallic disc 160 which engages near its periphery with a struck-in rib 162 on the container. The bottom of the container is formed by a stiff plate 164 having an opening for the rod 148 and other openings 165. Soldered to the container is a bellows 166 which forms a collapsible extension of the container and always is open to the atmosphere through the openings 165 and the hollow valve 150.

Fastened to the bottom of the bellows is a plug 168 which is frictionally gripped by the slit lower portion of a sleeve 170, the slits 172 making the sleeve springy with inherent tendency to grip the plug. The sleeve has its upper end flanged and supported by a head 174 at the lower end of the rod, the sleeve being free to rise from the head under certain conditions. The sleeve also prevents excessive collapse of the bellows.

Assuming the system is cold and the parts located as indicated in Fig. 7, when the heat comes on, the steam causes the bimetal disc 160 to flex upwardly as in Fig. 8. This closes the valve and lifts all of the parts in the casing except the rod 148. A period of heating ensues. When the heat dies down, condensation gradually forms a partial vacuum in the casing outside of the bellows. The bellows therefore stretches downwardly as indicated in Fig. 9, first pulling the sleeve 170 down onto the head 174 and away from the plate 164. When the sleeve thus becomes supported on the head 174, any further condensation and increase in vacuum tends to stretch the bellows upwardly, pressing the valve more tightly against its seat so that the valve will stay closed even after the bimetal disc snaps downwardly away from the rib 162 due to cooling. As further building up of vacuum occurs, the increased tendency to stretch the bellows downwardly overcomes the friction of the plug 168 in the sleeve 170 and the bellows, as indicated in Fig. 10, pulls the plug downwardly, the sleeve being held by the head. The bimetal disc snaps down away from rib 162 as cooling occurs. When heat again comes on, a little vapor pressure reduces the amount of vacuum and partially collapses the bellows downwardly from the top, thus lowering the container bottom 164 onto the sleeve 170 and opening the valve. This breaks the vacuum completely. The entering air at atmospheric pressure then collapses the bellows upwardly from the bottom overcoming the friction of the plug in the sleeve and pushing the plug upwardly to the first position of Fig. 7. The parts are now in the original position with the bimetallic disc about to snap upwardly again. The purpose of the friction device is to keep the valve lightly closed during all phases of the vacuum build-up prior to the entry of vapor so that, when a little vapor pressure does develop, the valve will open easily. In other words, the friction device limits the pressure exerted on the valve by the bellows and, by so doing, it also limits the amount of vapor pressure necessary to reopen the valve. As in the other forms, the friction limiting device compensates for variation in the degree of vacuum developed so that the valve will reopen upon a predetermined diminution of vacuum no matter how high the vacuum has built up. The closing bias of the bellows is desirable at the earlier stage in order to hold the valve closed when the bi-

metal disc snaps downwardly and so ceases to exert closing pressure.

In Fig. 11, a vacuum limiting device is applied to the valve of Fig. 7 and the friction plug is eliminated. The base 130 has an offset portion 176 provided with a screw threaded nipple to screw onto the furnace main. A circular rib or valve seat 177 on the base is engaged by a gasket 178 on a flanged plate or valve member 180 which is adjustably connected by a screw 182 to a plate 184 which is pressed upwardly by a coil spring 186. The spring surrounds a boss 188 which has an opening leaving a passage around the screw. The plate 184 is held from rotation during adjustment by a straight tongue 190 which fits between spaced lugs 192 on the boss 188. The spring normally keeps the valve closed but when condensation produces a predetermined vacuum, the downward elongation of the bellows brings the latter against the plate 184 and, as soon as the spring pressure is overcome, the valve opens slightly and momentarily so that incoming air brings the vacuum below the set maximum again.

Starting with the valve open and the system cold, the heat comes on and vapor pressure drives out the air. The steam causes the bimetal disc to snap up and close the upper valve. A period of heating ensues. When the heat dies down, condensation builds up a vacuum. The bellows accordingly stretches downwardly against the plate 184 and, until the spring pressure is overcome, the reaction is upwardly to keep the valve closed even if the bimetal disc snaps down. When the vacuum exceeds its set maximum, the lower valve opens enough to bring the vacuum back below the maximum. When the heat comes on again, the vapor quickly reduces the vacuum and the increase in pressure first collapses the bellows down from the top. This opens the upper valve and breaks the vacuum. The greater atmospheric pressure then collapses the bellows which jumps off the plate 184, this upward movement at the bottom occurring because the bellows is supported by the plate 164, the flanged sleeve 170 and the head 174. With the foregoing device, the vacuum never exceeds a set amount but the vacuum will nevertheless be broken when the heat is coming up in the furnace. By this vacuum limiting device, the friction devices of the preceding embodiment are eliminated. This device also operates as a relief valve to limit steam pressure.

In Fig. 12, there is shown a vacuum breaking valve adapted to be attached to a radiator instead of to the furnace main, the furnace main to have an ordinary vacuum valve which does not break vacuum but merely maintains it and opens to expel air. It is the intention to put one of these vacuum breaking valves on each radiator in the system and, as will appear, the valve on the easiest-to-heat radiator will open first, the entering air repelling the vapor and pushing it back in the pipes. The valve on the next easiest-to-heat radiator would next open and do likewise. Thus the vapor would have to go first to the hardest-to-heat radiator which is of course very desirable.

The valve is similar in many respects to the valve of Fig. 7 but the base has a lateral threaded nipple 200 for attachment to a radiator. The base also has a threaded plug 202 which is adjustable with respect to the friction plug 168. The plug 202 would be set for its respective radiator, being at a maximum distance from the friction plug 168 for the easiest-to-heat radiator and

at diminished distances for the harder-to-heat radiators in succession.

In use assuming a cold system and all valves open, the heat comes on and vents air through the ordinary vacuum valve on the cellar main and the radiator valves themselves. The valves all close when hot and stay closed when the heat goes off. As the system cools, a partial vacuum builds up and is held. When the heat comes on again, vapor pressure causes the valve on the easiest-to-heat radiator to open first because that valve has had the bellows stretched downwardly the most to reach its more remote plug 202 and hence the bellows can be more easily pushed down at the top to open the valve. The next easiest-to-heat radiator has the bellows stretched a smaller amount and it will be a little harder to open it, and so on. The hardest-to-heat radiator will thus be the last to open to the atmosphere but it will have been in a state of suction with respect to the hot vapors which are repelled from the other radiators and so this radiator will tend to heat first, giving a better balanced system. The venting capacity of these radiator valves of Fig. 12 is much restricted by adjusting the rods 148 upwardly by means of the set screws 146. Vacuum is thus broken slowly so that there is an interval in which the vapor can be driven to those points which need heating most. These valves can also be applied to piping, as when it is desired to repel vapor from one branch of a system to another.

In Fig. 13, a base 210 which is attached to a furnace main at V in Fig. 1 has a valve casing 212 soldered to it. The top of the casing is extended as a cap having a port 214 communicating with a passage in a seat member 216 with which a hollow valve 218 cooperates. The valve is attached to a bellows 220 having a bottom wall provided with a friction plug 222 engaged by the slit lower end of a flanged sleeve 224 supported on a collar or head 226 formed at the lower end of a supporting rod 228 suspended by the top of the casing. Below the bellows and spaced therefrom in the cold position is a thermostatic float 230 having an expansible top wall 232 and an expansible bottom wall 234, the latter resting at its center on a stud 236.

With the parts in the cold position indicated, the entrance of hot vapor expands the fluid in the float 230 and both end walls snap outwardly to the reversed position, the upper wall moving up against the bellows and closing the valve. After a period of heating, the fire dies down, steam condenses and builds up a partial vacuum. This causes elongation of the bellows which forces the plug 222 down in the sleeve 224 and forces the endwalls of the float nearer together. When the float 230 cools and returns to fully collapsed position, the valve remains closed because the bellows still presses upwardly from its friction support provided by the plug and sleeve. When heat comes on the pressure of the hot vapor (diminished vacuum) causes the bellows to collapse downwardly at the top sufficiently to open the valve and break vacuum. Atmospheric air pressure is equalized inside and outside of the bellows because the air can enter through the hollow valve 218 past the rod 228 as in Figs. 7 to 12 and the inherent spring action of the bellows causes the plug to slide up in the sleeve to starting position. The gap between the wall 232 and the bellows is never entirely closed when the float is cold and fully collapsed, even under conditions of maximum vacuum.

In Fig. 14, a two-part casing 240 with an aper-

tured cap 241 has a valve seat 242 against which a hollow valve 244 is adapted to seat. The valve is attached to a bellows 246 which is supported by a movable platform 248 having a flange 250 which is slit and springy, providing a sliding friction fit with the casing. The platform engages a thermostatic float 252 having a flexible bottom wall 254 engaging a stud 256. Lugs 257 struck from platform 248 center the float and provide openings 258 in the platform for communication between the upper and lower portions of the casing. An inverted cup 260 limits collapse of the bellows.

The valve is normally open to vent air. When heat reaches the float 252, the bottom snaps out, raising the platform and the bellows and closing the valve. After a period of heating, the steam condenses, building up a partial vacuum, thus tending to stretch the bellows. The valve remains seated and the bellows reacts against the platform, forcing the latter down as vacuum builds up. Cooling collapses the float letting the platform descend. When heat is renewed, the vapor pressure collapses the bellows downwardly at the top, breaking the vacuum.

I claim:

1. The method of operating a heating system, which consists in holding a partial vacuum in the system while the latter cools off, and causing a subsequent change of pressure of the heating medium itself to break the vacuum by letting in a substantial amount of outside air to put the system at atmosphere pressure near the beginning of a heating cycle.

2. The method of operating a heating system, which consists in holding a partial vacuum in the system while the latter cools off, supplying heat to the system, and causing the resulting change of pressure in the system itself to break the vacuum and put the system at atmospheric pressure near the beginning of a heating cycle.

3. The method of operating a heating system, which consists in holding a partial vacuum in the system while the latter cools off, and utilizing an increase of pressure in the system itself near the beginning of a heating cycle to control an inflow of a substantial amount of air to the system by opening the system to the atmosphere before said increasing pressure reaches atmospheric.

4. The method of operating a radiator heating system, which consists in holding a partial vacuum in the system while the latter is cooling off, utilizing an increase in pressure due to renewed heat to break the vacuum and restore the system to atmospheric pressure, venting the air from the radiators, and closing the system to retain the steam.

5. The method of operating a radiator heating system, which consists in holding a partial vacuum in the system while the latter is cooling off, supplying heat to diminish the vacuum, causing said diminution in vacuum to control the admission of air to the system, and utilizing the air to control venting from the radiators.

6. The method of operating a heating system having a plurality of radiators with vacuum valves on the radiators and piping connecting the radiators to a source of steam, which consists in supplying heat to the system, utilizing the resulting vapor pressure to open the valve on the normally easiest to heat radiator, causing air from outside of the system to first enter the normally easiest-to-heat radiator through said open valve to thereby drive the hot vapor back through the piping to a normally harder-to-heat radiator.

7. The method of operating a heating system having a plurality of radiators with vacuum valves on the radiators and piping connecting the radiators with a source of steam, which consists in supplying heat to the system, utilizing the resulting vapor pressure to open the valves on easier-to-heat radiators, and causing the hot vapor to enter the normally hardest-to-heat radiator by repelling, with air admitted from outside of the system, through the open valves, the vapor from easier-to-heat radiators.

8. The method of operating a heating system having a plurality of radiators and a valve on each radiator, which consists in causing all valves to close on the approach of steam and to stay closed while the system cools and builds up a partial vacuum, and causing an increase in pressure to first open the valve on the easiest-to-heat radiator to let in air from the outside of the system and thereby repel hot vapor to other radiators and to next open the valve on a less easy-to-heat radiator.

9. A vacuum breaking device for heating systems in which radiators are intermittently supplied with heat through piping from a steam boiler, said device comprising a casing, a valve and a valve seat, means for causing the valve and the valve seat to engage one another to hold the casing closed while steam is supplied and while a vacuum is building up, and means controlled by pressure in the casing itself for automatically limiting the pressure between the valve and its seat to facilitate their subsequent separation to admit air from the atmosphere at that point in the cycle when vacuum has stopped building up and has diminished a predetermined amount towards atmospheric pressure.

10. In a heating system having radiators, a vacuum breaking valve connected to the system at a point remote from the radiators, said vacuum breaking valve having means to hold the system closed under steam pressure and while a vacuum is building up when the steam condenses, said means including an extensible member responsive to pressure, and means for limiting the tendency of the extensible member to exert a closing bias on the valve as said vacuum builds up, whereby subsequent diminution of the vacuum at a point below atmospheric pressure can easily actuate the extensible member to open the system to let in air from the atmosphere, said last named means comprising a mounting for said extensible member constructed and arranged to automatically limit its valve closing bias caused by said building up of vacuum.

11. In a heating system having radiators, a vacuum breaking valve connected to the system at a point remote from the radiators and having thermostatic means to close it on the approach of steam, a bellows cooperating with the valve to hold the system closed while a partial vacuum builds up, and means for limiting the stress put on the valve by the bellows due to the partial vacuum to thereby avoid too tight closure of the system, whereby a small increase in pressure within the system at a point below atmospheric pressure will reactivate the bellows and open the system to admit air from the atmosphere.

12. In a heating system having radiators, a vacuum breaking valve connected to the system at a point remote from the radiators and having thermostatic means to close it on the approach of steam, a bellows cooperating with the valve to hold the system closed while a partial vacuum builds up, and a limiting device for preventing

such building up of vacuum from making the bellows put a heavy closing pressure on the valve.

13. In a heating system having radiators, a vacuum breaking valve having thermostatic means to close it on the approach of steam, a bellows cooperating with the valve to hold the valve closed while a partial vacuum builds up in the system, and a friction means cooperating with the bellows for limiting the stress induced in the bellows upon the closing of the valve under the partial vacuum condition.

14. A vacuum breaking valve having a casing and a valve seat, a valve adapted to engage the seat, thermostatic means to close the valve upon the heating of said means, a bellows cooperating with the valve to hold the valve closed while a partial vacuum builds up about said bellows, a friction member connected to the bellows, and a cooperating friction member having connection with the casing to frictionally resist movement of the bellows.

15. A vacuum breaking valve having a casing and a valve seat, a hollow valve adapted to engage the seat, a container connected to the valve, a bellows connected to the container, a thermostatic member acting to close the valve in the presence of heat, a sleeve within the bellows and having support from the casing, and a plug connected to the bellows and frictionally engaging the sleeve.

16. A vacuum breaking valve having a casing and a valve seat, a valve adapted to engage the seat, a bellows connected to the valve, a thermostatic container spaced from the bellows and adapted to engage the bellows on the approach of heat to close the valve, a friction member connected to the bellows, and a cooperating friction member having support on the casing.

17. In a heating system having radiators, a vacuum breaking valve having thermostatic means to close it on the approach of steam, a bellows cooperating with the valve to hold the valve closed while a partial vacuum builds up in the system, and a spring-pressed valve operable by one of the two parts comprising the bellows and the thermostatic means to limit the amount of vacuum in the system.

18. In a heating system having radiators, a vacuum breaking valve having thermostatic means to close the valve on the approach of steam, a bellows cooperating with the valve to hold the valve closed while a partial vacuum builds up in the system, and a vacuum limiting valve in the path of the bellows for operation thereby, as the increasing vacuum changes the length of the bellows, to limit the amount of vacuum acting on the bellows.

19. A vacuum breaker for heating systems in which radiators are intermittently supplied with heat through piping from a steam boiler, said breaker having a valve casing open to the system at a point remote from the radiators, a valve and a valve seat adapted to engage to close off the system from the atmosphere, means for causing pressure engagement between the valve and the seat while the system cools and builds up a vacuum, and a limiting means for automatically limiting the increase in pressure between the valve and the seat due to the building up of vacuum after the valve and the seat engage to thereby facilitate their subsequent separation.

20. A vacuum breaker for heating systems in which radiators are intermittently supplied with heat through piping from a steam boiler, said breaker having a valve casing open to the system

at a point remote from the radiators, a valve and a valve seat adapted to engage to close off the system from the atmosphere, means including a bellows, always exposed on one side to the atmosphere and on the other side to the system, for maintaining engagement of the valve and the seat while the system cools off and builds up a vacuum, and a limiting means co-operating with the bellows for automatically limiting the increase in pressure between the valve and the seat due to said building up of vacuum after said parts engage.

21. A vacuum breaker for heating systems in which radiators are intermittently supplied with heat through piping from a steam boiler, said breaker having a valve casing open to the system at a point remote from the radiators and having a valve and a valve seat engageable to close off the system from the atmosphere, a heat sensitive device and a bellows supported one over the other in the casing and the uppermost supporting one of said engageable parts, the bellows being exposed to the system on one side and exposed to the atmosphere on the other, the cooling of the system and the corresponding building up of vacuum tending to cause said bellows to exert an increasing closing pressure between the valve and the valve seat, and a limiting means co-operating with the bellows to limit the stress applied to the latter by the increasing vacuum and thereby prevent said closing pressure from continuing to increase.

22. A vacuum breaker for heating systems in which radiators are intermittently supplied with heat through piping from a steam boiler, said breaker having a valve casing open to the system at a point remote from the radiators, a valve and a valve seat engageable to close off the system from the atmosphere, pressure sensitive means to hold said parts engaged while the system cools and builds up an increasing vacuum, and means co-operating with the pressure sensitive means to enable the engaged parts to separate and break the vacuum completely whenever the vacuum has subsided a predetermined amount from its maximum.

23. A vacuum breaker for heating systems in which radiators are intermittently supplied with heat through piping from a steam boiler, said breaker having a valve casing open to the system at a point remote from the radiators, a valve and a valve seat engageable to close off the system from the atmosphere, a bellows exposed to the system for holding the valve and the seat in engagement while the system cools off and builds up an increasing vacuum, and a yieldable limiting means yieldable under increasing vacuum for automatically limiting the pressure between the valve and the seat whereby said parts will separate and break the vacuum completely whenever the vacuum subsides a predetermined amount from a maximum.

24. A vacuum breaker for heating systems in which radiators are intermittently supplied with heat through piping from a steam boiler, said breaker having a valve casing open to the system at a point remote from the radiators, a valve and a valve seat engageable to close off the system from the atmosphere, a heat sensitive member and a bellows supported one upon the other in the casing and acting jointly to control engagement and separation of the valve and the valve seat, the bellows being exposed on one side to the pressure of the system and the opposite

side having constant communication with the atmosphere, and a yieldable limiting means for limiting the pressure between the valve and the seat which an increasing vacuum in the casing tends to apply through the bellows.

25. A method of heating enclosed spaces by steam, utilizing a steam boiler, a source of heat, a plurality of radiators in said enclosed spaces and connected to said boiler in which each cycle comprises the following steps, setting said source of heat in operation at a predetermined falling enclosed space temperature, supplying said radiators with steam, venting air from said radiators, sealing the system, discontinuing the supply of steam, then allowing the steam to condense to create a negative pressure in said system, maintaining said system sealed, setting said source of heat in operation upon the repetition of the predetermined falling space temperature, supplying said radiators with hot vapor, admitting atmospheric air into the easiest-to-heat radiator through the utilization of the pressure of the hot vapor admitted thereto, to thereby drive the approaching steam back from said easiest-to-heat radiator to a harder-to-heat radiator.

26. A method of heating by steam, utilizing a system comprising a plurality of radiators with vents thereon and an intermittently operating source of steam, in which each cycle comprises the following steps: setting the source of steam in operation, supplying radiators with steam, sealing the system before or about the time the steam source ceases operation, discontinuing the supply of steam, then allowing the steam to condense to create a substantial negative pressure, and causing a subsequent diminution of said negative pressure to open said system to the atmosphere prior to distribution of steam to the radiators on the next heating cycle.

27. A method of heating by steam as set forth in the foregoing claim, in which the opening of said system to the atmosphere takes place when the negative pressure has decreased not more than four inches of mercury from the maximum negative pressure that is permitted to develop.

28. The method of operating a heating system having radiators in various locations which are not equally easy to heat and pipes connecting the radiators to an intermittently operating source of steam, which consists in closing the system on the approach of steam and holding the system closed while the system cools and condenses the steam to build up a partial vacuum, and causing the approach of a renewed supply of steam to first open to the atmosphere that part of the system which is easiest to heat to admit air from outside the system and thereby repel the hot vapor towards other parts of the system which are normally harder to heat.

29. In a steam heating system having radiators in different locations which are not equally easy to heat, a source of heating medium and pipes to conduct the heating medium to the various radiators, an adjustable vacuum breaking valve corresponding to each location, the individual valves being set to break vacuum at different vapor pressures, the location to which the heat can be driven easiest having the corresponding valve set to break vacuum at the lowest vapor pressure and thus admit air to drive the heating medium towards other parts of the system which normally are harder to heat.

HAROLD R. GOODALE.
